Alfred Schwarz, Inventor
By His Attorney, Chas. W. Mortimer

UNITED STATES PATENT OFFICE.

ALFRED SCHWARZ, OF MONTCLAIR, NEW JERSEY, ASSIGNOR, BY MESNE ASSIGNMENTS, TO COAL AND OIL PRODUCTS CORPORATION, OF NEW YORK, N. Y., A CORPORATION OF DELAWARE.

TREATING HYDROCARBONS.

Original application filed February 13, 1923, Serial No. 618,758. Divided and this application filed May 8, 1923. Serial No. 637,617.

This is a division of my application Serial No. 618,758, filed February 13, 1923.

In the treatment of oils the purpose of treatment is manifold, and the products, of course, are accordingly different. As the crude oils occur they are conglomerations of substances which, for the different uses have to be segregated and changed into classes which will be adapted for their individual uses. We have at atmospheric conditions, gaseous hydrocarbons, liquid hydrocarbons and solid hydrocarbons. These may be further subdivided into those containing only carbon and hydrogen, those containing carbon, hydrogen and oxygen, and those which contain in addition other constituents such as nitrogen, etc.

It is sufficient for the purpose of this patent application, to discuss the main classes, particularly those first mentioned.

In the treatment of such hydrocarbons, we deal with two distinct basic treatments, namely, segregation of compounds already existing, and the formation and segregation of new compounds formed. Due to the complexity of the chemistry of carbon, treatments given hydrocarbons often result in the change of the composition of the compound, intentionally or unintentionally, when in reality only segregation is thought of. On the other hand when changes are intended, new formations of compounds are often accomplished, either favorable or unfavorable to the result intended, and oftentimes such transformations are not recognized by the operator or chemist.

One of the objects of this invention is to afford means of control of such a segregation and reaction during treatment.

Other purposes of this invention are to produce an arbitrarily selected product of a given composition with predetermined boiling point, gravity, and other properties. In order to obtain such a product, compounds of great complexity and of varying properties must be combined and recombined chemically and finally separated from the mass of material employed.

For the purpose of explaining this invention, I will at present, confine myself to an operation having for its purpose a definite arbitrarily selected product, and while I de-

scribe the invention in such a manner, I do not wish to limit myself to any such particular operation, but I merely do this in view of the complexity of the subject, and to give a specific illustration of the invention.

In prior crude oil distillation processes, the naphtha cut was constantly removed from the oil under treatment, the intermediate products were used up and the operation came to a standstill. Had the conditions permitted the formation of new intermediates, new gasoline would be produced, but in view of the fact that in the practice of refining oil it has been found that with more heat and pressure more gasoline could be obtained, the natural tendency was to apply more and more of both until the limit was reached.

It is necessary, for the formation of chemical compounds, that the equilibrium between the reagents be not reached until the new compound is formed, and the reagent which caused the state of unequilibrium must be the one which is influencing the reaction in the direction of the desired product.

In making gasoline we aim to make essentially saturated hydrocarbons. The proportion of saturated and unsaturated hydrocarbons in the raw material, therefore, is controlled by the composition of the raw material and its treatment. It follows, therefore, that in order to convert a certain amount of raw material into a finished product of a predetermined specification, the composition of saturated and unsaturated hydrocarbons in the raw material must be properly proportioned.

In carrying out my invention it is essential to provide from some source the proper proportion of saturated and unsaturated hydrocarbons. The next requirement in carrying out my process is that a very intimate mixture of the reagents should be established and maintained.

The process comprises providing a combination of hydrocarbons capable of reacting with each other and maintaining that condition throughout the operation. It also comprises supplying hydrogen compounds with greater hydrogen content to compounds with lesser hydrogen content when it is intended

to produce compounds of higher hydrogen content and maintaining that condition throughout the operation.

In the accompanying drawing there is 5 illustrated an arrangement of apparatus for carrying out the invention. In the drawing:

Fig. 1 shows the arrangement of apparatus, parts being shown in section.

10 Fig. 2 is a section through the mixer.

Reference character 1 represents a still in which is charged crude or fuel oil high in unsaturated hydrocarbons, or similar type of high boiling point oils. This still may be 15 heated to any desired temperature, for example, 800° F. 2 represents another still containing lower boiling point hydrocarbons, for example, gas oil or kerosene. The oil in still 1 is principally unsaturated hydrocarbons, while the oil in still 2 is principally saturated hydrocarbons. Both oils are vaporized by boiling and the vapors pass through the mixing chamber 3 into the condenser 4 and from there into the separator 25 tank 5. Gases from 5 pass through the compressor 6 and are returned into the mixing chamber 3 where they are again recombined with new oil vapors coming from stills 1 and 2. Fresh oil may be supplied to the 30 still 2 from the tank 7, the circulation being maintained by means of the pump 8.

Fig. 2 shows a form of mixing chamber 3. Any design of a mixer, however, may be used. In the apparatus shown the reaction 35 takes place largely in the condenser 4 or at least during the period when the two vapors are mixed and gradually cooled. It is immaterial to the process whether the vapors get their reaction temperature during the 40 period downward from heating to cooling, or upward from hot to cold, as long as they are passed through a series of heat conditions in a thorough mixture of properly proportioned raw materials, and, at one stage or another, are subjected to the proper temperature conditions. It is, of course, understood that this system, the same as all other systems, can be elaborated upon by subdividing the one large step illustrated into 45 a series of smaller steps if so desired.

It is to be understood that the system may be conducted as a batch process. In order to provide the necessary hydrogen to reach the desired gravity and boiling points of the end product, it is necessary to continue the operation until in still 1, only heavy tar or coke is formed. In other words, until in still 1 a sufficient amount of carbon is extracted from the molecule to provide a proper hydrogen balance. It should be noted also that the vapors from still 2 are constantly circulated and this is done in order to provide all classes of intermediates to contact with each other. When gravity and boiling points are 50 reached then the liquor may be drawn off

from condenser 4 directly to a storage tank and new batches may be charged into the stills 1 and 2. Instead of distilling to carbon in the still 1 handling the crude or heavy oil, I may distill only to tar in this 70 still and obtain qualitatively the same results, but of course, in that case I will not obtain the full hydrogen content of the oil into the motor fuel product but a portion will be carried off in the tar. 75

Instead of passing the mixture from the mixer 3 directly to a condenser, this mixture may be heated to increase its temperature to any desired point in any convenient way as for example by passing the pipe carrying 80 the mixture through a furnace or any other convenient heating device, after which the mixture is led to the condenser 4.

Without intending to commit myself to any particular theory to account for the 85 results that have been obtained, I may say that the results have led me to believe that in a series of hydrocarbons ranging say from asphalt to gas, when heat is applied the hydrocarbons of lower hydrogen content 90 tend to combine with those of a higher hydrogen content, which in turn tend to combine with hydrocarbons of the next higher series and so on provided the proper proportions of saturated and unsaturated hydrocarbons exist at each step. Therefore, it is to be expected that hydrogen must be furnished. This, in effect, can be accomplished by increasing the proportionate content of hydrogen, as for example, by removing carbon from the hydrocarbons in any convenient way such as by cracking, thereby leaving a proportionately higher percentage of hydrogen in the hydrocarbon which is available for combination with the lower 95 range or series of hydrocarbons. 100

While I believe that it is necessary to have given proportions of saturated and unsaturated hydrocarbons, I do not limit myself to any particular degree of saturation but 110 I carry out my process through the medium of constantly diluting heavy fractions with lighter fractions, and I believe that reactions take place incorporating the bigger molecules, with the smaller molecules of the 115 lighter oils.

By my process individual hydrocarbons or groups of hydrocarbons may be vaporized under predetermined pressure and may be afterwards mixed under entirely different pressure conditions, the temperature of the mixture may be controlled independent of the vapor formation temperature of the component compounds, thereby obtaining products determined by experience and experimentation to be the ones desired as the end product of the process. This process therefore differs from prior attempts in that specially selected analyzed oils are vaporized 120 under given temperature and pressure or 125 130

vacuum conditions, the vapors are then mixed in a suitable mixing chamber and may then be subjected to a third pressure and temperature condition designed to produce the results desired.

As a specific illustration of this invention it may be mentioned that about 20% to 40% of saturated hydrocarbon vapors may be mixed with about 80% to 60% of unsaturated hydrocarbon vapors, the mixture subjected to this treatment and large yields of lighter or lower boiling point hydrocarbons may be thereby obtained.

I claim:

1. The process which comprises vaporizing predetermined proportions of low boiling saturated hydrocarbons and high boiling unsaturated hydrocarbons, mixing the va-

pors intimately, condensing the same and returning uncondensed hydrocarbons after compressing the same to the vapors that are being mixed.

2. The process which comprises distilling oil containing substantial amounts of unsaturated hydrocarbons substantially to dryness, mixing the vapors therefrom with vapors of low boiling hydrocarbons containing a high percentage of saturated hydrocarbons that are being continuously replenished by fresh low boiling hydrocarbons, condensing the mixture and returning uncondensed vapors to the vapors that are being mixed.

In testimony whereof, I have signed my name to this specification, this 5 day of May, 1923.

ALFRED SCHWARZ.
